UNITED STATES PATENT OFFICE.

GEORGE H. BLANCHARD, OF NORTHPOR, NEW YORK.

TOILET ACCESSORY.

Application filed June 29, 1921. Serial No. 481,231.

To all whom it may concern:

Be it known that I, GEORGE H. BLANCHARD, a citizen of the United States, and a resident of Northport, county of Suffolk, 5 and State of New York, have invented an Improvement in Toilet Accessories, of which the following is a specification.

The present invention relates to an improvement in toilet accessories, one object 10 being to provide a body rubbing or scrubbing device which will effectively serve the purpose among others of a wash cloth, bath sponge, or bath brush and which, after being used, may be thrown away. To produce an 15 article of the character referred to at a minimum price, and so that it may be included in the class of single service articles, if desired, a further object of the invention has been to utilize a fibrous or composite material of 20 an inexpensive kind and to treat it in such a way as to render it resistant to disintegration by water or abrasion at least during a normal single use of the device.

One embodiment of my invention is illustrated in the drawings accompanying the present specification, and in which—

Figure 1 is a bottom plan view,

Figure 2, a transverse section,

Figure 3, a transverse section of a modified 30 form,

Figure 4, a view illustrating the device approximately as retained by the hand in use, and

Figure 5, a detail view in section and on 35 an enlarged scale.

In producing an article embodying my invention, I preferably utilize a sheet of inexpensive fibrous or composite material such as pulp board approximately one sixteenth 40 of an inch in thickness. Where the board is flat, I deform it to provide abrasive or scrubbing projections or protuberances. This is conveniently accomplished by applying moisture and then subjecting the moistened board to a deforming operation by the 45 action of suitable dies by which I form the type of projections illustrated in Figure 3 of the drawings. It is contemplated that similar results in use may be obtained by employing a suitable material in which the protruding portions are previously formed, as 50 during manufacture in which case the fibres are not necessarily deformed or stretched. I do not limit myself to any particular shape

or arrangement of deformations or projections since it is obvious that the material may be deformed or preshaped to produce protruding portions of various shapes and sizes and arranged in various relative positions.

As shown in the drawings, a sheet of suitable material 1 is provided with projecting portions 2 preferably of a conical shape with slightly rounded ends presenting a relatively small contact or abrasive surface, said portions being produced by the action of the rolls or other suitable mechanism used in making the sheet. In the modification illustrated in Figure 3, the protruding portions 3 are die formed in the sheet when moist, or 60 in any other suitable condition. To be effective for the contemplated use, my improved toilet accessory is preferably resistant to disintegration when moistened or when subjected to abrasive action in the normal course 65 of use as an abrasive or friction appliance. A certain body conforming flexibility is also desirable although the article is preferably relatively rigid when dry so as to present a clean and attractive appearance. I do not 70 wish to limit myself to any particular type of medium or material for rendering the article resistant to disintegration. However, a coating of collodion or of paraffin applied to the surface of the sheet of material will 75 resist the disintegrating action of water and of abrasive contact with the body when in use.

The ingredient, such as collodion, which with the material of the sheet produces a 80 disintegration resisting member when applied to the sheet, is preferably of such consistency as to impregnate a portion of the fibrous or composite material adjacent to the surface at 8 as shown in Figure 4 and to 85 form a surface covering and encasing film or coating 9 enclosing the impregnated portion.

The coated or otherwise treated sheet of material will preferably be flexible when 90 moist so as to conform to the body when in use, and yet rigid enough to remain in extended condition. It will also be advantageous to provide means co-operating with the hand of a user for operatively retaining 95 the device in use. For this purpose, marginal recesses or indentations 4 and 5 are provided, or where both surfaces have pro-

tuberances, those on one side will, to a certain extent prevent slippage when the opposite side is being used as contemplated.

Where the accessory is to be used as an advertising medium, appropriate advertising data may appear in or on any appropriate portion of the sheet. For example, the deformations or protuberances may be grouped in such a manner as to form words, symbols or other indicia; or, suitable indicia may be printed, embossed or otherwise applied upon relatively undeformed end portions, as 6 and 7.

It is also contemplated that the device herein above described may incorporate or be treated with a scent producing ingredient of any desired characteristic so as to produce and agreeable odor either when dry or when moistened in the course of use, or both.

In Figure 3, I have illustrated a form of article in which increments of soap or of other cleansing or saponaceous substance are accommodated in the recesses opposite the protuberances. Of course, material for a similar purpose may be otherwise secured to, embodied in or operatively associated with the article.

I claim as my invention:

1. A bath accessory comprising a sheet of fibrous material normally absorbent but

having means insoluble by water to retard absorption, said sheet having a scrubbing portion.

2. A bath accessory consisting of a flexible sheet of fibrous material normally absorbent and disintegratable by moisture and having a plurality of protuberances integral therewith, said material being treated with a waterproofing material to resist sheet disintegrating absorption of water. 35

3. A toilet accessory comprising a sheet of absorbent material normally disintegratable by moisture, said sheet being provided with projecting portions and having a coating insoluble by water to render said sheet resistant to disintegration by moisture. 40

4. A bath accessory consisting of a sheet of fibrous material disintegratable by moisture provided with deformations projecting from the normally flat surface of the sheet 50 to present an abrasive surface and having a portion adjacent to the surface impregnated with a moisture resisting material to render the sheet resistant to disintegration by moisture. 55

In testimony whereof, I have signed my name to this specification this 28th day of June, 1921.

GEORGE H. BLANCHARD.
